ROLLING MILL

Hans Schimmel, Komotau, Czechoslovakia

Application April 28, 1932. Serial No. 608,065,
and in Germany May 4, 1931

2 Claims. (Cl. 80—13)

This invention relates to rolling mills for the manufacture of thin walled seamless tubes from a pierced or otherwise hollowed billet.

Heretofore, seamless thin walled tubes have been rolled from pierced billets, in rolling mills having two or four inclined, barrel shaped rolls, between which is fixed a mandrel mounted upon a mandrel shaft. When only two rolls are employed, guides are provided for stretching and rounding the tube. It has been proposed to provide hemispherical rolls, inclined if necessary, and to pass the piece to be worked between these rolls upon a movable mandrel. However, this construction of the rolls does not permit economical operation in practice.

It is, therefore, an object of the invention to improve the construction and arrangement of the metal working parts of rolling mills of this character, to permit economical operation.

20 In carrying out the invention, there is employed a cylindrical mandrel, freely movable in the rolling direction, together with a stretching and rounding bushing, in combination with rolls which form a reducing cone at the feeding opening, followed by a narrow transition zone and then an expanding zone.

These rolls are preferably disk rolls arranged at an acute angle to the tube feeding opening, and the stretching and rounding bushing is preferably mounted for longitudinal movement with respect to the path of the tube, in order to continuously present the metal to the stretching pressure.

In the accompanying drawings—

35 Figure 1 is a vertical section through a rolling mill according to the preferred embodiment of the present invention;

Figure 2 is a horizontal section through the same;

40 Figure 3 is a view similar to Figure 1, showing a modification; and

Figure 4 is a correspondingly modified view similar to Figure 2.

In these drawings, Figures 1 and 2 show a tube 10 which is carried by a central cylindrical mandrel 11. In the form shown, two or more disk rolls 12 are provided, which are mounted at an acute angle to the axis of the tube being rolled, the axes of the rolls being inclined toward the entrance end of the mill.

45 A stretching and rounding bushing 13 is interposed between the tube 10 and the mounting of the rollers 12. This bushing is cut away to form lateral openings through which the rollers project 55 inwardly into engagement with the tube on the

mandrel. The bore of the bushing 13 is inclined at the ends, resulting in a funnel-like construction.

In operation, the mandrel 11 passes through the rolling mill, with the tube 10 thereon. The 60 rolls 12, cooperating with the moving cylindrical mandrel, form the tube into a reducing cone, followed by a narrow transition portion, and a final expanding cone. The bushing 13, surrounding the expanding cone, causes the tube to be 65 stretched and rounded.

In the form shown in Figures 3 and 4, the rolls 12 are also mounted at an angle to the axis of the tube 10, but in this form the axes of the rolls 12 are at an obtuse angle to the tube-feeding opening. In these views, means are shown for advancing the bushing 13 in the direction of movement of the tube.

70 While electrical or mechanical means may be employed for this purpose, fluid pressure means, such as hydraulic cylinders 14 are shown. The cylinders 14 are mounted in the frame 15, in which the bushing 13 is slidably received.

Pistons 16 are mounted in the cylinders 14, and piston rods 17 extend therefrom, the ends of the 75 rods being adjustably connected to a yoke 18 carried by the bushing 13. The bushing may be constructed in two parts.

80 With this arrangement, the tube 10 on the mandrel 11 is passed into the rolling mill, and the rolls 12 engage the tube, and the action of the rolls and the moving cylindrical mandrel forms the reducing cone, narrow transition portion, and expanding cone, as described in connection with Figures 1 and 2. As the expanding cone is formed, 85 the bushing 13 is advanced by the cylinders 14 by means of the rods 17 and yoke 18. Thus the expanding cone engaging the bushing 13 which is advancing in the direction of movement of the tube, is stretched and rounded by the action of 90 the bushing.

95 The longitudinal movement of the bushing 13 is of advantage, particularly in conjunction with the longitudinally moving cylindrical mandrel, in that as the expanding cone is continuously formed, the same is continuously received by the advancing bushing, and thus a smooth and uniform operation is effected.

100 The tube discharged from the stretching rolling mill above described can be worked up or finished in a finishing apparatus or an expanding rolling mill followed by a reducing rolling mill.

I claim:

1. In a rolling mill for manufacturing seamless thin walled tubes from pierced billets or the like,

in combination, rolls having the axes thereof inclined with respect to the direction of movement of the piece being worked, a cylindrical mandrel movable in said direction of movement for feeding the piece to be rolled to said rolls, and a stretching and rounding bushing also movable in said direction of movement for receiving the tube formed by said rolls and continuously subjecting the same to the stretching pressure.

10 2. In a rolling mill for manufacturing seamless tubes, means for feeding the piece to be worked

comprising a cylindrical mandrel movable in the rolling direction; means cooperating with the moving cylindrical mandrel to form the tube into a reducing cone followed by a narrow transition portion and a final expanding cone, comprising disk rolls mounted at an acute angle to the tube feeding opening; and means surrounding the expanding cone for stretching and rounding the tube, comprising a bushing, and means for moving said bushing in the rolling direction.

HANS SCHIMMEL.
